UNITED STATES PATENT OFFICE

AUGUST LA GIER, OF LOS ANGELES, CALIFORNIA

DESIGN FOR A SANDWICH BOOTH

Application filed March 20, 1929. Serial No. 30,541. Term of patent 7 years.

To all whom it may concern:

Be it known that I, AUGUST LA GIER, a citizen of the United States of America, and a resident of the city of Los Angeles, in the county of Los Angeles and State of California, have invented a new, original, and ornamental Design for Sandwich Booth, of which the following is a specification, reference being had to the accompanying drawing, forming part thereof.

It will be understood that the opposite side of the design is the same as that shown in Figure 1.

I claim:

The ornamental design for a sandwich booth as shown and described.

Signed at the city of Los Angeles, county of Los Angeles, and State of California this 21st day of February, 1929.

AUGUST LA GIER.
